UNITED STATES PATENT OFFICE.

ELEAZER KEMPSHALL, OF NEW BRITAIN, CONNECTICUT.

HEEL-PROTECTOR FOR BOOTS OR SHOES.

SPECIFICATION forming part of Letters Patent No. 354,064, dated December 7, 1886.

Application filed August 21, 1886. Serial No. 211,555. (No modcl.)

To all whom it may concern:

Be it known that I, ELEAZER KEMPSHALL, a citizen of the United States, residing at New Britain, in the county of Hartford and State of Connecticut, have invented certain new and useful Improvements in Heel-Protectors, of which the following is a specification.

This invention relates to that class of heel-protectors which are to be inserted in the boot-heel, the object being to provide a protector adapted for insertion in the heel of rubber boots, as hereinafter more fully set forth.

In the drawings accompanying and forming a part of this specification, Figure 1 is a plan view of the under side of the heel of a rubber boot having inserted therein a protector embodying my invention. Fig. 2 is a side elevation, partially in section, of same. Fig. 3 is a horizontal section on line *a*, Fig. 2. Fig. 4 illustrates how the protector is placed in the heel-mold before the heel is pressed into shape. Fig. 5 is an enlarged plan view of the preferred form of protector before using. Fig. 6 is a side elevation of the same. Fig. 7 is a vertical section in line *b b* of Fig. 5.

Similar characters designate like parts in all the figures.

The mode of protecting heels made of leather by inserting in them metallic plugs is well known. In that case the plugs or cylindrical or conical pieces of metal are usually forced into holes made in the lower lift or layer of the heel, which lift or layer is afterward fastened into place. By this mode the protectors are readily fixed into place in leather boots; but in rubber boots the same mode is found insufficient. It is desirable in the latter case to secure the regular arrangement of the protector in a heel, while it is considered necessary to place them in the heel-mold before pressing them into shape. To insure, under these conditions, the desired result is one of the objects of my present invention.

My improved heel-protector comprises a series of wear-resisting plugs, preferably three in number, made of hard cast-iron or other hard metal, the several plugs being connected by a malleable bar in such a way as to constitute a single device, and the end plugs being furnished with placing-braces, as hereinafter de-

scribed. The plugs are preferably formed hollow, with the bar reaching across the interior opening, as shown in Fig. 5.

In the preferable form of metallic connection, the bar being malleable, the protector can be readily shaped by bending to fit any particular shape or size of heel, as shown in Fig. 4.

The bar 10 may be shaped to fit the dovetail recess 11, (shown in Fig. 7,) formed in the end of the plugs, or it may be round, as at 12 in the same figure. These wear-resisting plugs may be adjustably secured to the bar and placed thereon at different distances apart, to accommodate the protector to a greater range of heels. The metallic connections are more shallow in a vertical direction than the plugs, so that they are covered by the rubber of the heel when the plugs are so located as to be visible on the surface of the rubber.

One part of my improvement relates to the construction of the wear-resisting plugs used in the protector, whereby the plugs are adapted to be set securely in the yielding substance of rubber-boot heels. This improvement consists in making the plug in the form of a hollow cone, or other shape tapering toward the lower face of the heel, and in providing such plug at or near its base with an arm, 15, which serves a double purpose—as steadyng-bar and placing-brace. As will be seen, one of these arms 15 is provided for each terminal plug of the series.

The hollow plugs, when in place, are filled with a rubber core, 8, integral with the material of the heel, so that a much greater resistance is obtained against any sidewise displacement than would be with the plug in a separate piece from the heel.

I do not, however, limit myself to a hollow plug, as my invention is present in one of its forms when a series of plugs, either solid or hollow, is used in combination with skeleton connections between the plugs and with placing braces upon the terminal plugs.

The arms of placing-braces 15 and 13 are formed on the plug at or near its large end, as clearly shown in Figs. 6 and 7. These arms prevent the protector from being driven against the side of the heel-mold while the heel is being formed about the protector, and they resist

any force tending to tip the plug out of its vertical position. In this respect said arm co-
5 operates with the core in the hollow plug when the hollow plug is employed, and the connecting-arms also co-operate in discharging the same function. These terminal placing-braces may be made upon the plugs themselves, or in the form of my protector, in which the plugs are dovetailed upon the bar, or otherwise made
10 adjustable thereon. The placing-braces may constitute continuations of the rod, as shown in Fig. 4. Whether the arms are on the plug or are upon the arms extending beyond the plug, they are so shaped and located as to be
15 driven outward by the plastic material while under pressure in the mold. In this way the proper location of the series of plugs is secured, while the connecting bars and arms, being securely embedded in the rubber in the finished
20 heel, co operate with the integral core within the hollow plugs in holding the heel-protector firmly and permanently.

Having thus described my invention, what I claim as new, and desire to secure by Letters
25 Patent of the United States, is—

1. A wear-resisting plug for rubber-boot heels, consisting of a hollow frusto-conical plug having an arm or placing-brace projecting laterally from the base thereof, as set forth.

2. The combination, in a heel-protector, of 30 a series of wear-resisting plugs and a malleable connecting-bar, said plugs having openings for adjustment on said bar, substantially as described.

3. A heel-protector having a series of wear- 35 resisting plugs secured to a malleable bar connecting said plugs, in combination with arms or placing-braces, one at each end of the protector, all substantially as described.

4. The combination, in a heel-protector, of 40 a series of hollow plugs united by a bar extending through them, said plugs being adjustable thereon and the end ones having placing-braces at their sides, substantially as described, and for the purpose set forth. 45

5. A heel-protector consisting of a series of hollow frusto conical plugs united by a malleable bar extending through a recess in the end of the plugs, the plugs being adjustable on the bar and the end ones provided with an arm or placing-brace, as and for the purpose set forth. 50

ELEAZER KEMPSHALL.
